United States Patent Office

Des. 175,704
Patented Oct. 4, 1955

175,704

BUCKLE

Henning Af Odencrants, Sharon, Conn., assignor to North & Judd Manufacturing Company, New Britain, Conn., a corporation of Connecticut

Application March 28, 1955, Serial No. 35,231

Term of patent 3½ years

(Cl. D17—1)

Fig. 1.

Fig. 2.

The side opposite that shown in Figure 1 is substantially plain.

I claim:

The ornamental design for a buckle, as shown and described.
